UNITED STATES PATENT OFFICE

WALTER EVERETT MOLINS, OF DEPTFORD, LONDON, ENGLAND

METHOD OF AND MEANS FOR FORMING CIGARETTE AND LIKE PACKETS

Application filed July 23, 1928, Serial No. 294,843, and in Great Britain August 18, 1927.

This invention is for an improved method of and means for forming cigarette and like containers and more particularly to a machine adapted to form automatically a cigarette and like containers of the type which comprises a pair of pockets hinged together in such a manner that the open ends thereof are directed towards one another when the container is in an extended condition, and 10 wherein the hinge comprises a closure flap for the open end of the two pockets when one pocket is folded upon the other.

Packets of the above character have hitherto been formed from a single blank of paper 15 which comprises a substantially rectangular strip having two integral side extensions one at either end, which are arranged to be folded so as to lie above the strip and to be folded together with the strip, along either end and 20 along one side so as to form a container of the character above mentioned.

The blanks employed in forming such containers are expensive to manufacture due to the considerable waste of material which is 25 produced on account of the irregular outline of the blank. Further, the rate at which cigarettes may be packed in such containers is slow, and it is an object of the present invention to provide a method and means 30 whereby containers of the above character may be produced in a cheap and efficient manner and also to permit cigarettes to be automatically enveloped in such containers at a much greater speed than is possible with the 35 method at present employed.

The present invention consists of a method of manufacturing a double pocket container of the type referred to which comprises the following steps:—

(a) Automatically forming each pocket separately.

(b) Automatically arranging the separately formed pockets in pairs, and

(c) Automatically hinging the open ends 45 of each pair of pockets to one another by a closure flap which is arranged to extend across the open ends of the two pockets, when one pocket is folded upon the other.

Again, the present invention consists in a 50 machine for manufacturing a double pocket

container of the type referred to which comprises in combination means for moving a series of open ended pockets in succession, means for automatically arranging the pockets in pairs with their open ends located adjacent to one another and means for automatically hinging the open ends of each pair of pockets together by a closure flap which extends across the open ends of the two pockets when one is folded upon the other. 55 60

Further, the present invention consists of a machine for packing cigarettes in a double pocket container of the type referred to which comprises in combination means for automatically enveloping a batch of cigarettes in a U shaped block ended pocket open at one end, means for automatically arranging the filled pockets in pairs with the open ends thereof located adjacent to one another, and means for automatically hinging the open 65 70 ends of each pair of pockets together by a closure flap which is arranged to extend across the open ends of the two pockets when one is folded upon the other.

The invention is more particularly described with reference to the accompanying drawings wherein:—

Fig. 1 illustrates in elevation the pocket forming and filling mechanism of a machine constructed according to the present invention. 75 80

Fig. 2 illustrates a detailed view of the pocket forming mechanism illustrated in Fig. 1.

Fig. 3 illustrates the mechanism by which the pockets are fed in pairs to a reversing mechanism. 85

Fig. 4 is a plan view of that part of the machine wherein the pockets, after being formed and filled with cigarettes, are removed in pairs to the reversing mechanism, and thereafter sealed together to form a double pocket container. 90

Fig. 5 is an elevation of Fig. 4 viewed in the direction of the arrow "B". 95

Figs. 6, 7, 8 and 9 illustrate the mechanism by which the individual packets are stacked prior to the same being transferred to the reversing mechanism.

Fig. 10 illustrates in elevation the mecha- 100

nism employed for feeding pictures to the packets.

Fig. 11 is a detailed view of the picture feed.

Fig. 12 illustrates the blank from which each pocket is formed.

Fig. 13 is a perspective view of a container constructed according to the present invention showing the container in a partly 10 extended condition.

Fig. 14 illustrates the container shown in Fig. 13 in the closed condition, wherein one pocket is folded upon the other so that the hinge connecting the pockets constitutes the 15 closure flap for the open ends of the two pockets.

Figures 15 and 16 are fragmentary views in elevation illustrating in detail one form of mechanism for moving the pockets 20 through a heater box;

Figure 17 is a fragmentary elevational view of the magazine for receiving the pockets as they are ejected from the heater box; and

Figures 18 to 21 inclusive are fragmentary 25 sectional views on the lines C—C, D—D, E—E, and F—F respectively of Figure 4.

Referring to the drawings a pocket forming mechanism is mounted upon a frame 1 secured to the machine bed 2 and comprises 30 a reciprocating plunger 3 upon which the pocket is formed and thereafter stripped preferably by a device of the character described in U. S. Patent No. 1,091,235. The plunger 3 is guided by rollers 4 and 5 and 35 is reciprocated between a pair of parallel jaws 6 by any suitable means, such for example as by a rod 7 (Fig. 2) attached at its lower end to a connecting rod (not shown) and arranged at the back of the machine so 40 as to be operated by a crank driven by any suitable source of power. In operation the plunger 3 rises clear of the jaws 6 as shown in Fig. 1 for a short space of time during 45 which a blank of the character illustrated in Fig. 12 for making the pocket is fed across the top of the jaws 6.

The pocket blank comprises a rectangular strip of paper or like material B provided with an extension flap b (Fig. 12) and is 50 preferably fed from a stack or stacks depending upon whether different designs are to be illustrated upon the two pockets which constitute the finished container. If the two pockets comprising the finished container 55 are to have different designs thereon, a blank is fed alternately from one side and the other of the machine in the manner hereinafter described. The mechanisms for one blank feed will be hereinafter more particularly set 60 forth, but it is to be understood that a corresponding feed mechanism may be provided on the opposite side of the pocket forming mechanism and operable so as to feed alternately a blank to the pocket forming mechanism in the same manner as the blank feed

on the opposite side. The blank feed mechanism is mounted upon the frame adjacent to the jaws 6 and comprises a pair of rollers 8 which are adapted to rotate continuously at a uniform speed and a further pair of rollers 9 and 10 of which the roller 9 is arranged to rotate at a high speed and the roller 10 to act as a follower. The roller 10 is mounted upon a swinging lever 11 (Fig. 2) one end of which is secured to a rocking 75 spindle 12 carried in a bearing and projecting to the back of the machine, the arrangement being such that the roller 10 is brought momentarily into contact with the roller 9 at the desired moment.

A blank is fed by the feeding rollers 8 to the rollers 9 and 10 and as the latter is brought into contact with the high speed roller 9, the blank receives a sharp impulse which delivers it into position above the jaws 85 6 at the moment when the plunger 3 leaves the jaws and before or during its down stroke.

The operation of the roller 10 is controlled 90 in synchronism with the movement of the plunger 3 by the following means:—The rod 7 which operates the plunger 3 is fitted with a striking piece 13 which is adapted to engage with a pawl 14 secured to a spindle 12. As the rod 7 rises and carries the plunger 3 clear 95 of the jaws 6, the striking piece 13 engages with the pawl 14 and rocks the lever 11 so as to bring the roller 10 into contact with the roller 9 and thereby cause a blank to be fed beneath the plunger 3.

The spring 15 is adapted to return the parts 100 to their original position as the rod 7 moves downwardly.

The blanks B are placed in a housing 16 located on one side of the frame 1 and the 105 lowermost blank of each pile is adapted to be fed to the continuously rotating rollers 8 by means of an oscillating suction feed 17 preferably constructed according to U. S. Patent 1,419,466, British Patent No. 24,307 of 1914, 110 and U. S. Patent 1,382,213, each of the oscillating suction mechanisms 17 being operable 115 alternately through the medium of pivoted links 18 and 19 operated by cams 20 driven by the main shaft 19 of the machine, in such a manner that a blank from one stack is fed from the continuously rotating rollers 8 on one side of the machine whereupon the suction feed on the opposite side of the machine comes into operation.

Each blank "B" which may be automatically gummed along its two edges as it passes between rollers 8 is guided into position beneath the plunger 3 by a channel 21 fitted with a pivoted stop 22 arranged to permit a blank to be fed beneath the same from one direction but acts as a stop when a blank is fed in the opposite direction.

When the blank is located beneath the plunger 3, the same descends and carries the 130

blank through folding and stripping mechanisms which forms the same into a pocket open at one end and a blank is arranged to be located beneath the plunger 3 so that the extension *b* of the blank constitutes an extension to one broad side of the pocket.

The pocket upon being stripped from the plunger 3 is held between the sides of the heater box 23 which forms a lateral continuation of the jaws 6. The pocket in this position is pushed to the right by the reciprocating member 24 which is operable from the main drive of the machine by a cam through the medium of the pivoted links 25, 26 and 27. 10 15 This mechanism is illustrated in detail in Figure 15 of the drawings.

The pockets are intermittently fed along the heater box 23 in which the sides of the pocket are sealed together if the pocket 20 has previously been gummed. The leading pocket when it reaches the end of the heater box 23, swings through a right angle into the magazine 28 in the manner described in British Patent No. 166,406. The pockets are in 25 this manner fed downwardly to the bed 2 of the machine, falling over by gravity into the magazine as shown in Figure 17 of the drawings.

Mounted upon the end of the bed 2 of the 30 machine is a hopper mechanism 44, preferably constructed in accordance with the disclosures of British Patent 205,586 and U. S. Patents 1,497,576, 1,601,257, 1,688,982, and 1,668,693.

35 The cigarettes are removed from the vanes of the hopper mechanism by means of an endless conveyor 45 and conveyed thereby to the filling portion of the machine. The cigarettes are carried by the conveyor 45 between guides 46 into a mouthpiece 47 (Fig. 1). The mouthpiece 47 is mounted upon a swinging arm 48 pivotally secured at one end to the vertical magazine 28, and at the other end to the mouthpiece 47. The mouthpiece 47 is 40 held in its normal position by means of a spring arranged to hold the arm 48 away from the magazine 28. The under side of the mouthpiece is slotted to allow the pusher pieces 45a to pass through the same.

45 It will be appreciated that as the cigarettes are pushed into the mouthpiece 47 the latter is moved, against the influence of the spring controlling the swinging arm 48, into the mouth of the lowermost pocket located in the magazine 28, which is yieldingly held by means of a light spring 45b, until the cigarettes are completely inserted in the pocket.

50 The filled pocket is moved by the pusher piece 45 out of engagement with the mouthpiece 47 and is thereafter conveyed beneath the plate 62 into a delivery wheel, which comprises a pair of discs 70 (Fig. 6) which may be constructed of metal. The discs 70 rotate on a spindle 75 and grip the filled pockets between them and carry the same towards

an ejector. The ejector comprises a plate 72 pivoted at 73 (Fig. 1) and oscillated by a cam 74 mounted on the spindle 75 through a roller 76 against the tension of a spring 77. The plate 72 moves inward between the discs 70 and then outwards into a stacker 78. On moving inwards the plate 72 removes a pocket and then moving outwards under the action of the cam 74 delivers the pocket to the stacker 78 and pushes it along the same until the spring non-return catches 80 on the sides of the stacker prevent its return. The sides of the stacker may be heated by electric heater 81 and in order to relieve the pressure on the packet, one or both sides of the ejector may be movable by a cam at each stroke of the ejector, in the example illustrated in Fig. 1. One movable side 82 of the stacker is fitted with two long arms 83 each pivoted at 84 to the main frame 85 of the stacker. A rod 85 (Fig. 6) pivoted at 86, at one end is connected by a pin 87 to the side of the magazine 78, the other end of the rod carrying a roller 88 engaging with a crown cam 89 on the spindle 75. With this arrangement at every stroke of the ejector, a movement of the side 78 is obtained which limits the pressure on the pockets and allows the ejector to move them easily along the stacker 78. 90 95

It may happen that a batch of cigarettes is carried into the mouthpiece 47, but owing to the failure of the pocket feed, no pocket has dropped from the magazine on to the bed of the machine into the path of the oncoming cigarettes. The loose cigarettes will be carried forward, but in order to prevent any trouble occurring in the stacking apparatus, it is necessary to remove the loose cigarettes before they are delivered into the stacker. In order to effect this automatic operation, a sharp edged pawl 90 (Figs. 8 and 9) is pivoted on a spindle 91 over the channel along which the pockets pass adjacent to the delivery wheel and the pawl is normally held slightly below the level of the top of a filled pocket by a spring 92 (Fig. 8). When a filled pocket meets the pawl 90, the latter is lifted and rides lightly over the top of the pocket without damaging the same. If, 100 105 however, a loose batch of cigarettes meets the pawl, the latter drops between two adjacent cigarettes in the manner indicated in Fig. 9. As shown in Fig. 6 an arm 93 is secured to the spindle 91 and carries a pin 94 on which a hook shaped lever 95 is pivoted. The hook normally engages with a stop lever 96 held by a spring 97 and pivoted at 98. If the pawl 90 drops, the lever 95 also drops 110 115 releasing the lever 96 which, under the action of the spring 97, is oscillated about its pivot 98 causing the free end to fall and engage with an arm 99 secured to the ejector plate 72. The lever 96 prevents further inward movement of the ejector plate 72 and 120 125 130

65

thereby leaves a space between the discs 70 and the ejector 72 through which the loose cigarettes fall undamaged into a collector box (not shown). If the next group of cigarettes are enveloped in a pocket, the pawl 90 is raised and the hook on the lever 95 moves into position to engage with the stop lever 96, as soon as the latter is lowered. The lowering of the lever 96 is effected by a cam 100 on the back of one of the discs 70 which engages a roller 101 on the lever 96 swinging the same about its pivot into the desired position. The ejector plate 72 can then travel through its full stroke and stack the pockets 15 in the stacker. The delivery mechanism may be provided with a hinged cover 102 to prevent the pockets being thrown outward by the ejector. The hook 95 is free on the pin 94, but is controlled by a torsion spring 103 20 which twists it in a clockwise direction, a tail 104, on the hook engaging the spindle 91 to limit the motion of the hook. This arrangement gives flexibility to the action and ensures that the hook 95 will always operate 25 correctly. The hook 95 can only disengage from the stop lever 96 when the roller 101 is lifted by the cam 100. The action is timed to take place when a group is located beneath a pawl 90.

30 Due to the action of the ejector 72 the filled pockets are moved through the stacker 78 in steps. When the pockets reach the end of the stacker 78 an endless conveyor 105 is adapted to remove the leading pair of pockets 35 and convey the same upwardly through the channel 106 on to a bed 107 so as to locate each pair of pockets in the path of a conveyor 108. As the pair of pockets are carried upwards by the conveyor 105 the upper one is turned 40 over by means of a spirally twisted rail 109 acting in co-operation with a guide 110. The upper pocket of the pair is first displaced laterally with respect to the lower pocket by means of a projecting guide 109^a so that the 45 upper pocket overlaps the lower one and is able to lie upon the upper surface of the spirally twisted rail 109. As the upper pocket moves on the surface of the rail 109 its other face is acted upon by the guide 110 and when 50 the upper pocket reaches the position marked "C" on Fig. 4 it is standing on its edge on the surface of the lower pocket. The spring controlled arm 111 then causes the upper pocket to overbalance so that its outer surface now 55 becomes the inner surface in contact with the lower pocket. The upper pocket is restrained by a top guide 112 having side guides 113 at its forward end. When the pockets reach 60 the bed plate 107 the inner surface of the packets are in contact with one another and the extension flaps are on the outside. The lower extension flap is then turned vertically upwards as the pair of pockets are carried 65 along by the conveyor 108 by means of a

70 folder 114 fixed to the bed. This folder is of the usual spiral shape.

The packet is controlled during its movement along the bed plate 107 by means of a guide 115 and a top plate 116.

75 After leaving the folder 114 the packet passes by a gum wheel 122 running in a gum bath 123 and this applies a streak of gum to the remaining projecting flap. The gummed packet then passes along between the guide 115 and another guide 123^a and is delivered to a reciprocating table 124 at the bottom of a magazine 125. The table 124 is moved vertically upwards by means of a cam 126 and lever 127.

80 Three sides of the magazine are formed by brushes 128 and the fourth side is formed by an electrically heated plate 129. As the pairs of pockets are thrust upwardly into the magazine 125, the gummed flap of the upper pocket is bent down by the edge of the heated plate 129 and presses firmly on to the flap of the lower pocket. The pairs of pockets are retained in position in the magazine by means of small ratchet stops (not shown). 85 By the time the pairs of pockets reach the top of the magazine they are securely gummed together in the manner indicated in Fig. 14 and they may be removed by the operator for further treatment.

90 When it is desired to insert in the container of cigarettes a picture, coupon or the like, the picture is delivered to the bed of the machine prior to the cigarettes being inserted into the pocket. The cigarette pictures are preferably fed from a magazine 130 by means of a suction mechanism 131 preferably constructed in a similar manner to the blank feed described with reference to the pocket forming mechanism, and each picture is received by a pair of travelling bands 132, 133 and fed downwardly to a curved plate 134 which is adapted to lead the picture beneath the surface of the machine bed 2. A light pawl 135 is rocked by an eccentric 136 and at the correct time the pawl is reciprocated to carry the picture down to the center of the bed. The conveyor 45 then carries the picture along as indicated in Fig. 11 and the picture rises up the incline 136^a formed in the bed 110 2 until it is in contact with the group of cigarettes.

115 It is to be understood that a packet composed of two pockets may be formed without filling the same with cigarettes, in which case the conveyor 45 would be arranged to convey formers into the pocket delivered by the magazine 28 and a container composed of two pockets formed about said formers. The formers could thereafter be removed from 120 the packets and the packets filled by hand.

125 If necessary, the batch of cigarettes and picture may be inserted in foil, prior to the same being inserted into the pocket, the foil being either formed as a strip about the ciga- 130

rettes or into a **U** shaped block ended container in the manner described in British Patents Nos. 165,891 and 214,792.

Various methods may be employed in carrying the invention into effect without departing from the spirit of the present invention, thus for example the cigarettes may be wrapped in a strip of material fed vertically across the bed of the machine and thereafter formed into a **U** shaped block ended pocket open at one end. The mechanism in such case would be preferably constructed according to British Patent No. 165,891. Further, the pocket might be formed by the plunger method described, but the sealing of sides of the pocket performed after the cigarettes had been inserted in the formed but ungummed pocket, in which case the gumming and folding mechanism would be located between the pocket forming mechanism and the stacker 78.

Further, the pockets might be formed and filled upon one machine and secured together in pairs upon a second unit, in which case the pockets would not be automatically transported from one unit to the other.

What I claim as my invention and desire to secure by Letters Patent is:—

1. A machine for packing cigarettes or like articles in a double pocket container of the type referred to which comprises in combination means for enveloping a batch of cigarettes in a **U** shaped block ended pocket open at one end, means for arranging the filled pockets in pairs with the open ends thereof located adjacent to one another and means for hinging the open ends of each pair of pockets together to form a closure flap which extends across the open ends of the two pockets when one is folded upon the other.

2. A machine for packing cigarettes or like articles in a double pocket container of the type referred to which comprises in combination means for enveloping a batch of cigarettes in a **U** shaped block ended pocket open at one end and provided with an extension flap at one broad side thereof, means for arranging the filled pockets in pairs with the open ends thereof located adjacent to one another and the extension flap of one pocket located on the opposite side of the same relatively to the other pocket and means for securing the extension flaps together so as to form the hinge between the pair of pockets and constitute a closure flap for the open ends of the pocket when one pocket is folded upon the other.

3. A machine for packing cigarettes or like articles in a double pocket container of the type referred to which comprises in combination plunger operated means for forming a succession of **U** shaped block ended pockets each open at one end and provided with an extension flap at one broad side, means for locating each pocket in the path of a batch

of cigarettes so that the cigarettes are inserted therein, means for stacking the successively filled pockets of cigarettes with the open ends thereof located adjacent to one another, means for removing the pockets in pairs and arranging the same so that the extension flap of one pocket is located on the opposite side thereof relatively to the extension flap of the other pocket, and means for folding the extension flap of one pocket upon the extension flap of the other and securing the same together so as to form a hinge between the pockets and constitute a closure flap for the open ends of said pockets when one pocket is folded upon the other.

4. A method of packing cigarettes or like articles which comprises inserting batches of cigarettes in separately formed pockets having free extending flaps at the open ends thereof, arranging the filled pockets in pairs with the faces thereof juxtaposed and with the flaps located outwardly of the pockets, and securing the flaps on each pair of pockets together to form a hinge for the pockets adapted to close the open ends of the pockets when the latter are folded upon each other.

5. A method of packing cigarettes or like articles which comprises inserting batches of cigarettes in separately formed open ended pockets, arranging the pockets in pairs with their faces juxtaposed, and hingedly connecting the pairs of pockets together to form a flap which serves to close the open ends of the pockets when the latter are folded upon each other.

6. A method of packing cigarettes or like articles which comprises inserting a batch of cigarettes in separately formed **U**-shaped block ended pockets open at one end and provided with an extension flap at one broad side thereof adjacent the open end, arranging the pockets in pairs with the opposite broad sides juxtaposed, and securing the extension flaps of each pair together to form a hinge between the pockets and to constitute a closure flap extending across the open ends of the pockets when one pocket is folded upon the other.

7. A method of packing cigarettes or like articles which comprises forming **U**-shaped block ended pockets, each open at one end and provided with an extension flap at one broad side thereof adjacent the open end, inserting a batch of cigarettes in each pocket, arranging the pockets in pairs with the opposite broad sides juxtaposed, and securing the extension flaps of each pair together to form a hinge between the pockets and to constitute a closure flap extending across the open ends of the pockets when one pocket is folded upon the other.

8. A machine for packing cigarettes or like articles which comprises in combination means for forming a succession of open ended pockets, means for inserting a batch of cig-

arettes in each pocket, means for arranging the filled pockets in pairs with their open ends located adjacent to one another and means for hinging the open ends of each pair 5 of pockets together to form a closure flap which extends across the open ends of the two pockets when one is folded upon the other.

9. A machine for packing cigarettes or like articles which comprises in combination 10 means for feeding a series of open ended pockets in succession, means for inserting a batch of cigarettes in each pocket, means for arranging the filled pockets in pairs with their open ends located adjacent to one another and means for hinging the open ends 15 of each pair of pockets together to form a closure flap which extends across the open ends of the two pockets when one is folded upon the other.

10. A machine for packing cigarettes or like articles which comprises in combination means for forming a succession of U shaped block ended pockets each open at one end, means for inserting a batch of cigarettes in 25 each pocket, means for arranging the filled pockets in pairs with their open ends located adjacent to one another, and means for hinging the open ends of each pair of pockets together to form a closure flap which extends 30 across the open ends of the pockets when one is folded upon the other.

11. A machine for packing cigarettes or like articles which comprises in combination means for forming a succession of U shaped 35 block ended pockets each open at one end and provided with an extension flap at one broad side thereof, means for inserting a batch of cigarettes in each pocket, means for arranging the filled pockets in pairs with the extension flap of one pocket located on the opposite side of the same relatively to the flap of the other pocket and means for securing the extension flaps of each pair of pockets together to form a hinge between the pockets 40 and to constitute a closure flap for the open ends of the pockets when one pocket is folded upon the other.

12. A machine for packing cigarettes or like articles which comprises in combination 50 means for feeding blanks alternately from two distinct piles of blanks, means for forming the blanks so fed into open ended pockets, means for inserting a batch of cigarettes in each pocket, means for arranging the filled 55 pockets in pairs with their open ends located adjacent to one another and means for hinging the open ends of each pair of pockets together by a closure flap which extends across the open ends of the two pockets when one is folded upon the other.

13. In a machine for packing cigarettes or like articles, the combination with means for inserting batches of cigarettes into open ended pockets each having an extension flap 60 formed on one broad face of the pocket ad-

jacent the open end thereof, of means for feeding said filled pockets in succession with the broad faces on which the extension flap is formed directed downwardly, and means for superposing one of a pair of pockets on the other pocket of the pair with the broad face on which the extension flap is formed directed upwardly whereby the extension flaps of each pocket may be secured together to form a hinge connecting the two pockets and a closure for the open ends thereof when the pockets are folded upon each other. 70

14. In a machine for packing cigarettes or like articles, the combination with means for inserting batches of cigarettes into open ended pockets each having an extension flap formed on one broad face of the pocket adjacent the open end thereof, of means for feeding said filled pockets in succession with the broad faces on which the extension flap is formed disposed on the same side of each pocket, and means for superposing one of a pair of pockets on the other pocket of the pair in such manner the broad faces of the pockets on which the end flaps are formed are directed outwardly of the pair of pockets whereby the extension flaps of each pocket may be secured together to form a hinge connecting the two pockets and a closure for the open ends thereof when the pockets are folded 75 upon each other. 80

15. In a machine for packing cigarettes or like articles, the combination with means for inserting batches of cigarettes into open ended pockets each having an extension flap formed on one broad face of the pocket adjacent the open end thereof, of means for feeding said filled pockets in succession with the broad faces on which the extension flap is formed disposed on the same side of each pocket, and means for superposing one of a pair of pockets on the other pocket of the pair in such manner the broad faces of the pockets on which the end flaps are formed are directed outwardly of the pair of pockets whereby the extension flaps of each pocket may be secured together to form a hinge connecting the two pockets and a closure for the open ends thereof when the pockets are folded 90 upon each other. 95

16. In a machine for packing cigarettes or like articles, the combination with means for automatically forming a succession of open ended pockets, each having an extension flap adjacent the open end thereof, of means for inserting cigarettes in said pockets, means for feeding the pockets in superimposed pairs, a reversing mechanism for inverting the upper pocket of each pair so that the extension flaps are disposed on opposite sides 100 110 115 120 125 130

of the pair of pockets, and means for folding and securing the flaps together across the open ends of the pockets to form a closure therefor when the pockets are folded.

5 In testimony whereof I hereunto affix my signature.

WALTER EVERETT MOLINS.
